UNITED STATES PATENT OFFICE

2,630,318

OPERATOR FOR JALOUSIES AND VENETIAN WINDOWS

Luther Owen Conner, Tampa, Fla., assignor to
Maestre's Industries, Ltd., a corporation of Brit-
ish Honduras

Application October 12, 1951, Serial No. 251,072

1 Claim. (Cl. 268—96)

1

This invention relates to an operator for jalousies and Venetian windows.

An object of this invention is to provide an improved operator for jalousies and Venetian windows whereby the slats may be readily adjusted and firmly secured or locked in their adjusted position.

Another object of this invention is to provide an operator which is designed to be attached to the frame of the jalousie or Venetian window and connected to the tie bar or link at one end of the slat structure so that the tie bar may be vertically adjusted and secured or locked in adjusted position.

A further object of this invention is to provide an operator of this kind which is simple in construction and will not readily get out of order.

With the above and other objects in view, my invention consists in the arrangement, combination and details of construction disclosed in the drawing and specification, and then more particularly pointed out in the appended claim.

In the drawing:

Figure 1 is a detail side elevation of an operator for a jalousie or Venetian window constructed according to an embodiment of this invention.

Figure 2 is a sectional view taken on the line 2—2 of Figure 1.

Figure 3 is a sectional view taken on the line 3—3 of Figure 1.

Referring to the drawing, the numeral 10 designates generally a frame structure within which slats 11 are pivotally mounted, and the slats 11 have disposed at each end right angular mounting plates 12 which are pivoted on pivots 13. The inner ends of the mounting plates 12 have pivotally connected therewith a vertically disposed connecting bar 14, the bar 14 being connected to the plates 12 by means of a pivot 15. Vertical movement of the bar 14 will provide for simultaneous rocking of all of the slats 11.

In order to provide a means whereby the bar 14 may be vertically rocked and locked in adjusted position, I have provided an operator generally designated as 16. The operator 16 comprises a plate 17 formed with a base flange 18 secured by fastening means 19 to the inner side of the frame 10. The plate 17 is of substantially semi-circular configuration at its inner end and is formed with an obtusely disposed flange 20.

A plate 21 is disposed in spaced relation to the inner portion of plate 17, having a semi-

2

circular inner edge and an obtusely disposed flange 22 which is parallel with flange 20. Plate 21 is secured to plate 17 by offsetting opposite portions of plate 21 as indicated at 23, and securing the offset portion 23 to the plate 17 by fastening devices 24.

A tie bar operating lever 25 is pivotally secured between plates 17 and 21 on a pivot member 26 which engages through plates 17 and 21. The outer end of lever 25 has pivotally mounted thereon a short link 27, and the link 27 is pivotally connected as at 28 to tie bar 14. The inner end of lever 25 is obtusely bent, as indicated at 29 and is externally threaded for receiving a locking nut or knob 30.

A substantially U-shaped washer 31 is mounted on the stud or bent inner portion 29 of lever 25 and the parallel sides 32 of washer 31 engage on the outer sides of flanges 20 and 22, as shown in Figure 2.

In the use and operation of this device the operator 16 is secured to the inner edge of frame 10 by the fastening devices 19, and link 27 is pivotally connected to tie bar 14. Tie bar 14 is vertically moved and locked in adjusted position by partially unthreading knob or nut 30 and then rocking lever 25 upwardly or downwardly. When tie bar 14 is adjusted to position the slats 11 in the desired position, knob or nut 30 is tightened so as to tightly bear washer 31 against the arcuate edges of flanges 20 and 22.

While plate 17 is herein shown as being fastened to frame 10 by fastening devices passing through flange 18, in certain installations plate 17 may be secured to frame 10 by fastening devices 24 which will hold the assembly together as well as secure the assembly to the supporting frame.

I do not mean to confine myself to the exact details of construction herein disclosed, but claim all variations falling within the purview of the appended claim.

What I claim is:

45 In a jalousie or Venetian window structure having pivoted slats and a vertical tie bar connected to the slats, an operator for adjusting said slats, said operator comprising a plate, a right angular base flange carried by one end of said plate for attachment to a support, a semi-circular obtusely angled flange carried by the opposite end of said plate, a second plate shorter in length than said first plate, a pair of offset members carried by said second plate, means 50 securing said offset members to said first plate 55 to thereby dispose said second plate in spaced

parallel relation to said first plate, a semi-circular obtusely angled flange at the inner end of said second plate parallel with said first flange, a lever between said plates, a pivot for said lever extending between said plates, an obtusely disposed stud extending from said lever and engaging between said flanges, a nut threaded on said stud, a U-shaped washer on said stud between said nut and said flanges, a link pivotally secured to the outer end of said lever, and means 10 pivotally securing said link to said tie bar.

LUTHER OWEN CONNER.
